UNITED STATES PATENT OFFICE.

ABRAHAM D. BORENSTEIN, OF BROOKLYN, NEW YORK.

HOSE SUPPORTER.

Application filed March 11, 1925. Serial No. 14,719.

This invention relates to a hose supporter. The object of the invention is the production of a hose supporter or garter, by means of which it can be easily and securely suspended 5 from a garment and to which, hose, stockings and the like can be easily attached. The second object of the invention is the production of a hose supporter that consists of simple and inexpensive parts, that can be quickly 10 and cheaply assembled.

The organization of the invention comprises a main strap, which has connected to its upper end double means for attaching it to a garment, and which has suspended therefrom 15 a lower strap comprising a pair of members. The latter have each connected thereto a stud frame or stud plate, for a tapered stud that is adapted to lock with the loop of a clasp.

20 In the accompanying drawings Fig. 1 represents a front elevation of the improved hose supporter suspended from a garment; Fig. 2 shows a section of Fig. 1 on the broken line 2, 2; Fig. 3 is an enlarged view of a 25 modification of the hose supporter; Fig. 4 indicates a section of Fig. 3 on the broken line 4, 4; Fig. 5 represents a plan view of a detail and Fig. 6 is a left hand side view of Fig. 5.

30 The main strap 20 of the hose supporter preferably comprises a piece of webbing, at the upper end of which is indicated an ordinary safety pin with its bar 21, pin proper 22 and its keeper 23. A clevis is indicated 35 with its lower member 27 and the hook ends 28. The said hook ends are suspended from the pin 22. At the upper end of the strap 20 is formed the loop 30, which extends over the lower member 27 of the clevis. A U 40 shaped clamping bracket 32 with its serrated lower edges 33 is clamped over the loop 30 with its serrated edges engaging the opposite faces of the strap 20. A garment is indicated at 38 with the depending strap 39, 45 that has formed therewith the loop 40 at its lower end for supporting the bar 21 of the safety pin. A button 41 is connected to the strap 39, by means of the heavy tread or cord 42. A strap with the members 44 and 45 ex- 50 tends over the cord 42 and said members have formed at their lower ends loops 46, which latter extend around the pin 22. Eyelets 47 clamp each of the ends of the loops 46, and the members 44 and 45. A U shaped 55 clamping bracket 49 with the serrated ends 50, clamps the loops 46 to the pin 22.

To the lower end of the strap 20 is detachably clamped a buckle 53, comprising the rear plate 54 with the opening 55. Ears 56 extend from the plate 54. A wing 58 is hinged 60 to the ears 56. A loop 60 with the upwardly extending member 61 is formed at the lower end of the strap 20.

A lower strap extends through the opening 55 of the buckle 53 and is shown with the pair 65 of members 66 and 67. The members 61, 66 and 67 are connected together by the eyelets 68.

To the lower end of each of the members 66 and 67 of the lower strap is connected a 70 clasp, designated in its entirety by the numeral 70. Each clasp 70 comprises the usual lower loop 71 with the curved lower end 72, the upper loop 73 with the bar 74. The lower ends of each of the straps 66 and 67 extend 75 through the upper loop 73 and have formed therewith a loop 75 with the upwardly extending member 76. The upper end 79 of a strap 80 is located between the member 76 and its strap 66 or 67, and eyelets 81 clamp 80 together the straps 66 and 67, the ends 79, and the members 76 adjacent thereto.

A stud frame designated in its entirety by the numeral 85 is supported in the lower end 85 of each of the straps 80. Each of the frames 85 comprises the central body portion 86 which has formed therewith the annular loops 87, forming the openings 88 and 89. A thimble 90 with the end flanges 91 and 92 extends from the frame 85 and through the opening 93 in the central portion 86 thereof. A tapered stud 95 is supported on the thimble 90. The smaller end of the stud 95 bears against the central body portion 86 of the frame 85, and a washer 96 is located between 95 the upper end of the stud 95 and the flange 91.

Each of the straps 80 extends through the opening 88 of its stud frame, then extends through its other opening 89 thereof. It next returns upwardly as indicated at 98 and again enters the opening 88. In the modification indicated in Figs. 3 and 4, one of the members of the lower strap is again indicated at 67 with its clasp 70 comprising the lower loop 71 with its curved lower end 72, the upper loop 73 with the bar 74. The lower end of the member 67 extends through the loop 73 again forming the loop 75 and then extends upwardly forming the member 100, then returns downwardly forming the member 101. At the lower end of the member 101 is formed the loop 102, and from the 105 110

latter extends the upwardly extending member 103, which bears against the member 100. A pair of eyelets 105 clamp together the member 67 and the members 100 and 103.

5 A stud plate 108 bears against the member 103 and has formed therein an opening 109. An eyelet 110 connects the plate 108 and the member 103. A thimble 112 extends from the plate 108 and through its opening 109.

10 Flanges 113 and 114 are formed at the ends of said thimble. A tapered stud 115 is shown with its small end 116 and its large end 117. The said small end 116 bears against the member 103. A sleeve 120 with the flange 121 is supported on the thimble 112, the flange 121 bearing against the flange 114. The said flange 121 also bears against the large end 117 of the stud 115. It will be noted that the safety pin indicated with the bar 21,

15 and the pin proper 22 has its bar 21 suspended from the depending strap 39 of the garment 38, and that the pin proper 22 is supported by the members 44 and 45, which in turn are suspended from the depending

20 strap 39 of the said garment. There is thereby provided two means for suspending the main strap 20 from the depending strap 39.

25 Various modifications may be made in the invention and the present exemplification is to be taken as illustrative and not limitative thereof.

Having described my invention what I desire to secure by Letters Patent and claim is:

1. In a hose supporter the combination of

a lower strap, a stud frame supported by the strap, a thimble having flanges at its ends extending from said frame, one of the flanges of the thimble bearing against a face of the frame, a tapered stud encircling the thimble with its smaller end bearing against the frame, 40 a washer encircling the thimble interposed between the larger end of the stud and the adjacent flange of the thimble and a suspended clasp coacting with said stud.

2. In a hose supporter the combination of 45 a lower strap, a loop formed at the lower end of said strap, an upwardly extending member formed with said loop, a second strap having an upper folded end, said end located between the said lower strap and its 50 upwardly extending member, eyelets connecting said lower strap, extended member and folded end, a stud frame having a central body portion and a pair of annular loops, said second strap extending through said 55 annular loops to support said frame, a thimble having flanges at its ends extending from said frame, one of the flanges of the thimble bearing against a face of the frame, a tapered stud encircling the thimble with its smaller end bearing against the frame, a washer encircling the thimble interposed between the larger end of the stud and the adjacent flange of the thimble and a clasp suspended from the loop of the lower strap coacting with said stud.

In testimony whereof I affix my signature.

ABRAHAM D. BORENSTEIN.
